UNITED STATES PATENT OFFICE.

JOHN SCHREIBER, OF ST. LOUIS, MISSOURI.

THREAD-WAXING DEVICE FOR SEWING MACHINES.

Original application filed May 21, 1921, Serial No. 471,314, now Patent No. 1,440,556, dated January 2, 1923. Divided and this application filed December 11, 1922. Serial No. 606,082.

To all whom it may concern:

Be it known that I, JOHN SCHREIBER, a citizen of the United States, residing at the city of St. Louis and State of Missouri, have 5 invented a new and useful Thread-Waxing Device for Sewing Machines, of which the following is a specification.

This invention relates to sewing machines, and has special reference to the thread wax- 10 ing device.

An object of the invention is to provide an improved thread waxing device for applying wax to a thread passing to the stitching mechanism of the sewing machine from 15 a roll or spool of thread.

The subject-matter of the present invention is divided from my prior application Serial No. 471,314, filed May 21, 1921, patented January 2, 1923, No. 1,440,556, and 20 an additional object of the invention is to provide equipment for the sewing machine of my said prior application for waxing the thread passing to the stitching mechanism thereof.

25 In the drawings, Fig. 1 is a sectional view of the invention applied to a machine of the type mentioned.

Fig. 2 is a plan view of the device.

The sewing machine in connection with 30 which the invention is shown comprises a housing 1 having a bracket 2 attached thereto for supporting a spool or roll of thread 3. The strand of thread 4 from the spool passes through a hole or eye in a lateral extension 35 5 of the bracket 2 and thence through an eye 6 supported by the front head housing of the sewing machine. The thread 4 is for the formation of a lower loop in the stitching, and the wax applying device is located between the eye 6 and the stitching 40 mechanism.

The wax applying device comprises a wax pot 7 that is slidably mounted on a rod 8 extending downwardly from the bottom of 45 the front head frame. A set screw 9 is provided for supporting the wax pot in different adjusted positions on the rod 8. A cover 10 for the wax pot is likewise mounted for adjustment on the rod 8 above the top of the wax pot, the cover being held in different adjusted positions by a set screw 11 arranged for clamping engagement with the rod 8.

An arm 12 extends downwardly from the inner side of the cover 10 and has a slot 55 13 in its lower end through which the thread

4 passes. The cover 10 has an opening 14 in its rear edge, through which the thread 4 passes to the slotted eye 13 at the lower end of the arm 12. From the slot 13 at the lower end of the arm 12 the thread 4 passes upwardly through an opening 15 near the front of the wax pot cover 10 and thence through an eye 16 and a hole 17 to the stitching mechanism.

A scraper device in the form of a flat 65 spring 18 is attached to a web 19 extending from the arm 12. The thread 4 moves between the spring 18 and the web 19 so that excess quantities of the wax carried up by the thread from the bottom of the wax 70 pot are scraped off, it being understood that a supply of wax in semi-liquid form is maintained in the wax pot to about the depth shown.

The spring 18 is held in place by a screw 75 20 which may be adjusted to vary the pressure of the spring against the thread in order to cause the spring to function properly in scraping off excess quantities of wax.

From the foregoing it will be seen that my 80 invention is a simple and efficient one for obtaining all of its intended objects and purposes. The device may be readily applied to and removed from the sewing machine and conveniently set in different adjustments. I am aware that the invention 85 may be varied in equivalent particulars without departure from the nature and principle thereof, and do not restrict myself unessentially, but what I claim and desire 90 to secure by Letters Patent is:—

1. In a sewing machine, a wax receptacle, a cover for the receptacle, an arm in connection with said cover extending downwardly into the receptacle, a web rigid with 95 the cover within the receptacle, and a spring within the receptacle for engaging and pressing the thread against said web to remove excess quantities of wax from the thread passing through the receptacle.

2. In a sewing machine, a housing, a support extending from the housing, a wax receptacle, means for holding the wax receptacle in different adjusted positions on said support, a cover for the receptacle, 105 means for holding the cover in different adjusted positions relative to the receptacle, means supported by the cover for guiding one of the threads downwardly through the receptacle, and a scraper device supported 110

by the cover within the receptacle between said guiding means and the point at which the thread leaves the receptacle for scraping excess quantities of wax from the thread 5 passing through the receptacle.

3. In a sewing machine, guides for a thread passing to the machine, a wax receptacle, a cover for said receptacle having an opening through which the thread may 10 pass into the receptacle and another opening through which the thread may pass out of the receptacle, means supported by the cover for guiding the thread through the receptacle, and a scraper device supported 15 by the cover in the receptacle between said guiding means and the opening through which the thread passes from the receptacle for scraping excess quantities of wax from the thread.
- 20 4. In a sewing machine, a wax receptacle, a cover for the wax receptacle, one of said parts being provided with an inlet opening for the thread and one of said parts being provided with an outlet opening for the 25 thread, a guide in rigid connection with one of said parts for guiding the thread toward the bottom of the receptacle, a web in rigid

connection with one of said parts between said guide and the outlet opening for the thread, and a spring attached to said web 30 for scraping wax from the thread passing between web and said spring.

5. In a sewing machine, a wax receptacle, a removable cover for said receptacle, means for supporting said receptacle and said cover independently of each other, a projection on the cover extending toward the bottom of the receptacle and having a notch in its lower end for thread passing through the receptacle, a spring supported by the cover 40 inside the receptacle, and a rigid part supported by the cover for cooperating with the spring to scrape wax from the thread.

6. In a sewing machine, the combination of a wax receptacle, a cover for said receptacle, means for supporting the receptacle and the cover in different adjusted positions relative to each other, a thread guide supported by the cover for the thread passing through the receptacle, and a scraper 45 supported by the cover inside the receptacle for scraping wax from the thread passing through the receptacle.

JOHN SCHREIBER.
